UNITED STATES PATENT OFFICE.

GOTTFRIED BEGAS, OF BERLIN, GERMANY.

ANCHOR.

No Drawing.

Application filed July 24, 1922. Serial No. 577,089.

To all whom it may concern:

Be it known that I, GOTTFRIED BEGAS, a citizen of the German State, residing at No. 16 Aschaffenburgerstrasse, Berlin, W. 30, 5 Germany, have invented a certain new and useful Anchor, of which the following is a specification.

The present invention relates to a so-called folding or patent anchor and its principal distinguishing feature is that the two flukes together are heavier than the remainder of the lower portion of the anchor, so that the flukes of the anchor according to this invention grip immediately they 10 touch the ground owing to the position of their centre of gravity and furthermore that the flukes immediately penetrate further into the ground at the spot where the anchor is dropped.

20 In folding anchors as hitherto constructed and consisting of a stem and two arms which are provided with flukes and are pivoted to the stem and rotate conjointly through an angle of about 90°, the centre of gravity of 25 the whole arrangement lies in the vicinity of the centre of the pivot bolt. This type of anchor has also a base plate which lies in the centre of the arms of the flukes and is rigidly connected thereto. The lower part 30 of this plate, which, in the idle position in which the flukes lie in a plane with the stem, is situated at right angles to this latter, serves, after the anchor has been dropped and after tension has acted on the stem of 35 the anchor, to effect a rotary movement in a direction opposite to that in which the anchor is pulled, and thereby to turn the flukes downwards into the ground.

As, however, in these known anchors, the 40 weight of the flukes is extraordinarily small in comparison with the weight of the arms of the anchor, the plate, the pivot member and the lower end of the stem, these anchors do not, in most cases, grip bottom at once, 45 but are frequently dragged for considerable distances before doing so. In ground which is unsuitable for anchoring, for instance, ground which is covered with weeds or ooze, these anchors either do not grip bottom at all or do so only in an unreliable manner.

In a bed of weeds, for example, an anchor of the kind hitherto known sinks with its heavier part gradually deeper and deeper, 55 while the comparatively light flukes tend to revolve with the arms about the pivot and

to point upwards and consequently do not grip.

All these disadvantages are obviated by the anchor according to the present invention and in a satisfactory manner. The important feature of the anchor according to the present invention is that both flukes together are heavier than the remainder of the lower portion of the anchor. Accordingly the lower part at least of the stem the arms of the anchor and the pivot member are made of comparatively light weight, by shaping them suitably, while yet retaining perfect stability, so that, for example, when such an anchor is sunk into weed-covered ground, the points of the flukes, in contradistinction to the known anchors, first penetrate and then on sinking in deeper grip effectively owing to the arms and stem 75 of the anchor lagging behind. The like result is obtained when the anchor sinks into other kinds of ground, such as that which is oozy or composed of sand.

When the anchor according to this invention is suspended from the chain, it sets itself in such a position, by reason of the particular distribution of the weight, that the stem does not lie in line with the chain but obliquely thereto and consequently the 80 points of the flukes are from the outset located considerably nearer to the horizontal plane while the anchor is being lowered into the water than is the case with the anchors hitherto known the stem of which 85 hangs practically vertical in line with the chain.

In the case of very small anchors which can be thrown by hand, the technical advantage of the anchor according to this invention is that these anchors, when sufficient chain is paid out, will settle in the water with their flukes pointing downwards with the result that they grip bottom whichever way they turn. This is important because 100 the drifting of small boats, as well as large ships, from the place where it is intended to anchor involves great danger of stranding and damage owing to the proximity of the 105 unnavigable waters or the coast.

The anchor according to this invention grips bottom at once at the place where it touches the ground and on further traction being exerted on it buries itself to its maximum depth in the ground at this point so 110 that the safety of both ship and crew are thereby very considerably augmented.

I claim:

1. An anchor provided with pivoted fluke-bearing arms, the said flukes forming the heaviest portions of the anchor.
5. 2. An anchor in which the flukes carried by arms are heavier than the remaining parts of the anchor.
3. An anchor comprising pivoted arms carrying integrally formed flukes thereon,
- 10 the said flukes together being heavier than

the remaining parts of the anchor, the weight of the flukes being so distributed that the flukes normally assume a position at an angle to the shank of the anchor on either side thereof.

GOTTFRIED BEGAS.
